UNITED STATES PATENT OFFICE.

FREDERICK G. FOLBERTH AND WILLIAM M. FOLBERTH, OF CLEVELAND, OHIO, AS-
SIGNORS TO TRICO PRODUCTS CORPORATION, OF BUFFALO, NEW YORK, A CORPORA-
TION OF NEW YORK.

WINDSHIELD CLEANER.

Application filed October 17, 1924. Serial No. 744,269.

This invention relates to windshield cleaners, and more particularly to improvements in suction motors employed in connection with windshield cleaners of the type described and claimed in the patent to William M. Folberth, granted February 7, 1922, No. 1,405,773.

An object of the invention is the provision of an improved valve shifting mechanism 10 for a windshield cleaner motor, wherein a floating lever is employed by means of which greater leverage is obtained.

In the construction of windshield cleaner motors, the valve mechanism heretofore employed consists of a pivoted lever arranged in the path of a moving part of the motor and a pivoted valve supporting member connected thereto. The levers are connected to each other at points remote from their pivots by means of a spring which is adapted to store up energy during the initial movement of the first lever and to positively move the second lever to shift the valve when the piston or movable element approaches the 25 end of its stroke.

In the present invention, we employ a third lever, designated as a floating lever and arranged between the first lever and the spring. This lever is so arranged that during the initial movement of the first lever, or valve actuating member, the leverage exerted on the spring is increased and the energy stored in the spring without affecting the movement of the piston. At an appropriate time, the movement of the floating lever is arrested and the spring functions in its ordinary manner.

A further object of the invention is the provision of means for retaining the cleaning arm in a raised position at the end of a stroke when the cleaner motor is cut off.

In the accompanying drawings, we have shown several embodiments of the invention. In this showing:

45 Figure 1 is a perspective view of the motor and cleaner arm assembled,

Figure 2 is a central vertical sectional view of the cleaner in position on a windshield,

50 Figure 3 is a vertical sectional view on line 3—3 of Figure 2,

Figure 4 is a similar view on line 4—4 of Figure 2,

Figure 5 is a horizontal sectional view substantially on line 5—5 of Figure 1,

55 Figure 6 is a view of a part of the motor in the same plane as Figure 4, showing the valve and the valve shifting mechanism in its other alternate position,

Figure 7 is a detail view of the valve and 60 valve shifting mechanism disassembled,

Figure 8 is a perspective view of a closure plate on which the valve mechanism is assembled,

Figure 9 is a view similar to Figure 2 65 showing another form of valve shifting mechanism,

Figure 10 is a view similar to Figure 3, showing another form of the means for retaining the cleaner arm in raised position, 70 and,

Figure 11 is a detailed disassembled view 75 of the valve and valve actuating mechanism shown in Figure 9 of the drawings.

Referring to Figures 1 to 8 of the drawings, the reference numeral 1 designates a windshield of a motor vehicle formed of glass or other transparent material and mounted in a suitable frame 2. The windshield cleaner consists of a motor 3 adapted to be arranged on the windshield frame and secured thereto in any suitable manner. The motor is provided with a transverse shaft 4 which extends through the frame and a cleaner arm 5 is arranged adjacent the outer end thereof. This cleaner arm is provided with a holder 6 on its lower end adapted to receive a cleaner element consisting of a backing strip 7 of metal or other rigid material and a strip of rubber 8 which is adapted to contact with the surface of the windshield to be cleaned (see Figure 2). The motor shaft also extends from the inner side of the motor casing and is provided with a handle 9 to permit manual operation.

90 More particularly the motor is formed of two substantially cup-like sections 10 which may be formed of drawn sheet metal and which are provided with flared inner ends 11. As shown, the outer ends of the sections are closed as at 12, forming the heads of the cylinder, and the inner ends are adapted to be secured to each other to form a cylinder. A closure or body plate 13 is arranged adjacent the junction of the inner 105 ends of the two sections of the cylinder and

this closure plate is curved in cross section (see Figures 1 and 8) and is adapted to extend partially around the cylinder. The inner face of the closure plate is provided 5 with an enlargement 14 adapted to form a support for the valve and valve operating mechanism. A band 15 of resilient material is secured to the upper and lower edges of the closure plate and encircles the meeting 10 edges of the cylinder sections to secure them to each other. As shown, this band is provided with a V-shaped groove 16 in its inner face, adapted to receive the flared ends 15 of the cylinder section. The outer face of the closure member is provided with a substantially T-shaped rib or boss 17 and the upper end of the clamp is enlarged, as at 18, and secured to the top of this rib by means of screws 19. The lower end of 20 the band is provided with openings adapted to receive lugs 20 projecting from the face of the closure plate.

A pair of pistons are mounted within the cylinder and retained in spaced relation. As 25 shown, each piston consists of a pair of disks 21 of metal or other rigid material. These disks are slightly smaller in diameter than the internal diameter of the cylinder and a sheet of packing 22 is arranged between them. As shown, the sheet of packing is of larger diameter than the cylinder forming a skirt 23. The pistons are connected to each other by a connecting member 24, which is preferably formed of sheet 30 metal and is provided with ends 25 extending at an angle to the body of the connecting member. Screws 26 are arranged in openings in the disks 21 and the ends 25 of the connecting member. As shown, the connecting member is provided with spaced openings 27 and is adapted to serve as a rack in transferring the movement of the pistons to the shaft. An arcuate shaped plate 28 is arranged on the shaft and this plate is 35 provided with teeth 29 forming a segmental gear adapted to mesh with the teeth 27 of the rack. As shown, the portion of the plate above the shaft is extended parallel to the shaft, as at 30 (see Figure 2) and is 40 then provided with a downwardly extending portion 31 having an opening for the passage of the shaft by means of which the gear is provided with a double bearing.

The enlargement 14 on the inner face of the closure plate is provided with an inwardly extending sleeve 32, forming a bearing for the shaft, and the shaft extends through an opening 33 formed in this sleeve and passing through the closure plate. The other end of the shaft is received in a bearing 34 formed in the ends of the cylinder sections and a collar or spacing member 35 is arranged on the shaft between the extension 31 of the segmental gear and the cylinder wall (see Figure 2).

The opposite ends of the cylinder are adapted to be connected to a source of suction by means of passages extending through the closure plate. As shown, the closure plate is provided with a main suction passage 36 having a tube 37 arranged therein and the end of this tube is adapted to be connected to a source of suction, such as the intake manifold of an internal combustion engine (not shown) by means of a suitable 70 conduit (not shown). As shown, the main suction passage extends transversely of the T-shaped rib on the exterior of the closure plate or longitudinally of the cylinder. The end of this passage communicates with an inclined passage 38 extending inwardly to the inner face of the enlargement 14 (see Figures 2 and 8). Suitable means are provided for manually controlling the passage of fluid through the passages 36 and 38. 85 An inclined passage is formed in the T-shaped rib adjacent the point of communication between the passages 36 and 38 and this inclined passage is internally threaded 90 for the reception of a valve stem 39. The inner end of the valve stem is provided with a valve member 40 adapted to engage a seat formed at the junction of the passages 36 and 38 to permit these passages to be disconnected from each other. The outer end 95 of the valve stem is provided with a suitable handle 41 and a spring 42 is arranged on the valve stem. A cylinder passage 43 is arranged on each side of the suction passage 38 and these passages extend outwardly in 100 a substantially horizontal plane, as shown in dotted lines in Figure 2 of the drawings. The outer ends of these passages are connected to longitudinally extending passages in the T-shaped rib and suitable tubes or 105 conduits 44 which extend longitudinally of the cylinders and are connected to the opposite ends of the cylinders through openings 45 arranged adjacent each end.

The valve actuating mechanism consists of an actuator in the form of a lever 46 which is substantially semi-circular in shape to fit around the sleeve 32 and which is pivotally mounted on the sleeve. As shown, the sleeve is provided with a rib 47 on its upper side having a groove or bearing 48 formed therein. The forward end of this groove is closed by a block 49. The valve actuating lever is provided with a loop 50 at its upper end and the end of this loop is arranged parallel to the body portion, as at 51. These parallel portions are provided with depending members 52 having rounded lower ends adapted to fit in the groove 48 to pivotally support the lever. The lower end 120 of the lever is provided with a depending arm 53 adapted to engage spaced pins 54 carried on the face of the segmental gear. A substantially cup-shaped valve 55 is arranged on the inner face of the enlargement 125 130

14 and is adapted to cover the central suction passage and either one of the cylinder passages to establish communication between the source of suction and either end of the cylinder (see Figure 5). This valve is provided with a stem 56 adapted to be received in an opening 57 in one of the arms 58 of a substantially U-shaped valve supporting member or carrier. The base of the 10 valve supporting member is provided with depending arms 59 adapted to engage a pin 60 carried on the face of the enlargement to limit the movement of the valve. The pin 60 is preferably formed of rawhide or other 15 non-metallic material to reduce the noise occasioned by the shifting of the valves. The upper ends of the arms 58 are pointed, as at 61, and are adapted to be received in grooves or bearings 62 formed in enlargements 63 on the bottom of the sleeve 32, to 20 pivotally support the valve supporting member. The valve supporting member and the valve actuating lever 46 are connected to each other by means of a coil spring and a 25 spring-positioning member in the nature of a floating lever. As shown, the floating lever consists of a substantially semi-cylindrical member 64 adapted to fit around the sleeve 32 provided with an opening 65 adjacent its upper end. The upper end of the 30 valve actuating member and the arm 51 arranged parallel thereto are provided with aligned notches 66 adapted to receive the reduced ends 67 of a roller 68. One end of 35 this roller passes through the opening 65 in the floating lever and the body portion of the roller retains the lever in the desired vertical plane (see Figure 2). The upper 40 end of the floating lever is provided with an arm or extension 69 received in a cut out portion in the closure plate. The end of this 45 cut out portion forms shoulders 70 which are engaged by the arm 69 to control the movement of the floating lever. The lower 50 end of the floating lever is provided with a notch 71 adapted to receive one end of a coil spring 72 and the opposite end of this 55 spring is connected to the base of the U-shaped valve supporting member.

50 Means are provided for retaining the cleaner arm in raised position at the end of a stroke when the motor is cut off. As shown, a pin 73 extends from the arm 31 to the body portion of the segmental gear and this 55 pin passes through a substantially elliptical-shaped member 74. The pin is secured to the elliptical-shaped member on one of its long sides and at a point directly opposite, a coil spring 75 is connected thereto and the 60 other end of this spring is connected to a projection 76 formed on the upper portion of the cylinder wall.

65 In the form of the invention shown in Figures 9 to 11 of the drawings, the construction and operation is essentially the

same. The construction of the motor casing, closure plate, shaft and segmental gear are the same as that heretofore described, and the same reference numerals are employed to designate the various parts. In place of 70 the valve actuating lever 46, we employ a lever 77 which is also substantially semi-cylindrical to fit around the sleeve 32 and which is provided with a depending lower end 78 to engage the pins 54. The upper 75 end of the valve actuating lever is provided with a loop 79 similar to the loop 50 and is further provided with an extension 80 parallel to the body portion. Between the body portion of the lever and the extension 80, 80 there is provided an arm 81 extending at right angles to the body portion and having a depending end 82 arranged parallel to the body portion and the extension 80 and disposed between them (see Figure 9). In 85 place of the roller 68, we employ a pin 83 adapted to pass through aligned openings in the body portion of the lever, the depending end 82 and the extension 80. The floating lever 64 is arranged between the parts 80 90 and 82, as shown in Figure 9 of the drawings, with the pin 83 passing through the opening 65 and these parts serve to properly space the floating lever and retain it in 95 the desired plane.

In Figure 10 of the drawings, we have shown another means for retaining the cleaner arm in raised position when the motor is cut off. As shown, the extension 31 of the segmental gear is provided with an 100 opening adjacent its lower end, adapted to receive one end 84 of a spring. The spring consists of resilient arms 84 and 85 connected to each other by a loop or coil 86. The arm 85 is secured to the top of the 105 motor casing, as at 87.

In the operation of the form of the invention shown in Figures 1 to 8 of the drawings, the tube 37 is adapted to be connected to a suitable source of suction and the valve 55 is adapted to be shifted by the movement of the pistons in the cylinder to alternately place the opposite ends of the cylinder in communication with the source of suction. With the parts in the position shown in Figure 5 of the drawings, the left end of the cylinder is in communication with a source of suction and the pistons are moving to the left. At the end of a stroke, the valve is shifted to cover the central suction passage 38 and the right cylinder passage 43 to place the opposite end of the cylinder in communication with the source of suction.

In Figures 4 to 6 of the drawings, the valve is in the same position as in Figure 5, connecting the left end of the cylinder to the source of suction. The position of the pistons and segmental gear in Figures 4 and 5 is at the end of a stroke just after the 120 125 130

valve has shifted. When the pistons begin the movement toward the left end of the cylinder, the segmental gear 28 oscillates in a clockwise direction. The pin 54, which has just moved the valve actuating member 46 to its present position moves away from this member and the pin 54 to the right of the center of the segmental gear approaches the valve actuating member as the stroke is continued. Adjacent the end of the stroke, the pin 54 contacts with the lower end 53 of the valve actuating lever. The valve actuating lever, being pivoted in the groove 48 swings on its pivot. As the floating lever 64 is connected to the valve actuating lever by means of the roller 67, the upper end of this lever moves from the position shown in Figure 4 of the drawings, in engagement with the left stop 70 to the position shown in Figure 6 of the drawings, in engagement with the right stop 70. It will be noted that the leverage exerted is in proportion to the distance from the pin 54 to the groove 48 on one side of the fulcrum and from the groove 48 to the roller 68 on the other side of the fulcrum. This affords a great leverage during the movement of the valve actuating member to a substantially central position during which time energy is stored in the spring 72. As the upper end of the floating lever is swung to the right by the valve actuating lever, the lower end moves toward the right and upwardly, placing the spring under tension. At the time that the valve actuating lever passes the central position, as shown in Figure 6 of the drawings, the movement of the floating lever is arrested by the shoulder 70. The system of levers, forming a compound lever, connected at one end of the spring 72, produces a novel and exceedingly practical snap action for an automatic valve mechanism. After the actuating lever 46 begins its movement, its longer depending arm requires but a slight force to move said lever on its fulcrum, the shorter arm lever above the fulcrum carrying the pin 67 with the lever 64 mounted thereon in a bodily manner until the arm 69 of said lever 64 comes in contact with the obstructing shoulder 70. At this point the lever movement takes a decided change. The lever 64 is no longer bodily moved but assumes its character as a lever, obtaining its fulcrum on the shoulder 70 where the arm 69 is engaged. The actuating lever 46 then acts on the pin 67, which may be considered as being located at the outer end of the shorter arm of said lever 64, to swing the lower or free end of the longer arm of said lever 64 to which the spring 72 is connected. Up to this time the bodily movement of the lever 64 has been relatively slow by reason of the fact that it is bodily supported for such movement on the shorter arm of the actuating lever 46. Conse-

quently the end of the spring 72 which is engaged in seat 71 of said lever 64 will also be slowly moved toward a dead center position relative to the pivotal mounting of the valve carrier 58. At the moment that the lever 64 engages its fulcrum point, or stop 70, the slow movement of the shorter arm of lever 46 will be considerably multiplied at the lower or free end of the longer arm of said lever 64. In other words the spring carried end 71 of said lever 64 will have its spring shifting movement accelerated decidedly as said spring 72 is shifted across a dead center position. Obviously after the spring 72 has been shifted across a dead center position, the then tensioned spring will pull the valve carrier 58 to its other position. The pistons then will reverse their movement.

It will therefore be noted that the energy required to place the spring 72 under tension is expended on the longer end of said lever 46, and that the boost or acceleration required to carry the spring across dead center is practically momentary. Thus the valve action embodies a compound lever which permits a gradual storing up of energy in the valve shifting spring, and then, when the storing up of the energy has been practically completed, the slow energy storing movement of the spring is accelerated or given a boost sufficient to carry it across dead center.

It will also be noticed that the auxiliary spring device 74, 75, (84, 85, 86) will also be expending its stored up energy in assisting the rotation of the wiper shaft 4 at the moment when the valve spring 72 is given its boost or acceleration. In this respect, the auxiliary spring device 74, 75 (84, 85, 86) is having energy stored up therein during the first portion or half of each shaft movement, and during the latter portion or half of each movement of the shaft said auxiliary spring device is expending its energy to not only urge the wiper element toward the end of its stroke, but also of necessity assist in giving the valve spring movement an acceleration or boost.

The member 74 shown in Figure 3 of the drawings, swings with the shaft as it is oscillated and at the end of each stroke, the parts are in the position shown in Figure 3 or in a similar position on the opposite side of the shaft. Heretofore, there has been a tendency for the cleaner arm to move downwardly from the position shown in Figure 1 of the drawings to the position shown in Figure 2 of the drawings, due to the weight of this member and its associated parts. In order to move downwardly in the present construction, it is necessary to exert sufficient force to place the spring 75 under tension and by properly proportioning the strength of the spring movement of the

cleaner arm, is prevented. It will also be noted that this member tends to assist in the equal distribution of energy throughout the stroke of the piston. During the first part 5 of the stroke of the piston, no energy is being stored in the spring 72 and the only force being expended by the cleaner is the force necessary to move the blade 8 over the surface of the windshield. When the spring 10 75 is employed, it is also necessary for the motor to place this spring under tension during the first part of the stroke. During the latter part of the stroke when energy is being stored, in the spring 72 of the valve 15 actuating mechanism, the energy stored in the spring 75 during the first part of the stroke is released, and the movement of the pistons is thus equalized.

In the form of the invention shown in 20 Figures 9 to 11 of the drawings, the operation of the valve actuating member is essentially the same as that heretofore described. In this form of the invention, a pin 83 of substantially uniform diameter throughout 25 is employed in place of the roller 68 and the extension 82 is employed for the purpose of maintaining the floating lever in the desired vertical plane. The spring 84 also functions in the same manner as the spring 75, 30 exerting an upward pull when the cleaner blade is at the end of a stroke and tending to hold it in this position if the motor is cut off.

The provision of means whereby a great 35 amount of leverage is obtained during the initial movement of the valve actuating member when energy is being stored in the spring 72 and the leverage ratio reduced after the energy has been stored and just 40 before the movement of the spring and valve is a decided improvement in view of the fact that the amount of power available for the operation of a windshield cleaner motor is limited and at times, when the engine of 45 the vehicle is laboring under a load and the throttle valve is wide open, the vacuum in the manifold and the energy available for the operation of the cleaner motor is reduced to practically zero. Under such conditions, 50 the cleaner motor has a tendency to slow down and by increasing the leverage employed for storing energy in the spring 72, this tendency may be partially, if not wholly, overcome.

55 The herein described subject matter relating to the windshield cleaner construction has been divided from this application, the same forming a part of our co-pending application filed April 20, 1925, Serial No. 60 24,602.

It is to be understood that the forms of our invention herewith shown and described are to be taken as preferred examples of the same, and that various changes in the shape,

size, and arrangement of parts may be re- 65 sorted to without departing from the spirit of the invention or the scope of the subjoined claims.

We claim:

1. A snap over valve mechanism for fluid 70 motors comprising a valve, a carrier therefor, a spring connected at one end to said valve carrier and adapted to store up energy to effect a movement of the valve at the end of each stroke, and a system of levers connected to the opposite end of the spring for being actuated by a movable part of the motor to actuate said spring, and having a greater leverage during its initial movement when energy is being stored in said spring 80 and a shorter, quicker-acting leverage during the later movement just before said spring effects a movement of the valve.

2. Valve actuating mechanism for wind- 85 shield cleaners comprising a casing, a mov- able member mounted in said casing, and a valve to alternately place said casing on op- 90 posite sides of said movable member in com- munication with a source of differential pressure, said valve actuating mechanism comprising a movable valve supporting member, a valve actuating member con- 95 trolled by said movable member, a member pivotally connected to one end of said valve actuating member, and a spring connecting the opposite end of said pivotally connected member and said valve supporting member.

3. A device constructed in accordance with 100 claim 2 wherein means are provided on the last-mentioned member to coact with a fixed part of the casing for limiting the move- 100 ment of one end of said valve supporting member.

4. Valve actuating mechanism for wind- 105 shield cleaners comprising a casing, a mov- able member mounted in said casing, and a valve to alternately place said casing on op- 110 posite sides of said movable member in com- munication with a source of differential pressure, said valve actuating mechanism comprising a movable valve supporting member, a movable valve actuating member controlled by said movable member, a mem- 115 ber pivotally connected at one end to said valve actuating member, and a spring con- necting the other end of said pivotally connected member and said valve supporting member.

5. In a motor for windshield cleaners, a 120 valve, a pivoted carrier therefor, a spring connected at one end to the carrier, means connected to the opposite end of the spring for moving it to opposite sides of dead center relative to the pivotal mounting of the carrier, means operable from a moving part 125 of the motor for accelerating the movement of the first means as said opposite end of the spring approaches a dead center position

and continuing such acceleration as said first means carries its connected end of the spring over dead center.

6. In a motor for windshield cleaners, a valve shiftable from one to another of two positions, resilient means movable to initially store up energy and subsequently to expend the stored up energy in effecting a shift of the valve, means operable by a moving part of the motor for so moving said resilient means, and means for effecting an acceleration in the movement of the second means as the resilient means approaches its maximum limit of energy-storing movement for effecting a comparatively quick change-over to the energy-expending movement of the resilient means.

7. In a motor for windshield cleaners, a body plate having a valve seat and a shaft bearing, a valve cooperating with the seat, a carrier for shifting the valve on its seat, said carrier having pivotal support on the bearing, an actuating lever operable from a moving part of the motor and fulcrumed on the bearing at a point circumferentially spaced from the carrier point of support, and power-transmitting resilient means extending about the bearing to operatively connect the carrier and the lever and yieldingly hold the same pivotally supported on the bearing against displacement.

8. In a motor for windshield cleaners, a body plate having a valve seat, a valve on the latter, a carrier for the valve having pivotal support on the plate, an actuating lever operable from a moving part of the motor and having an oppositely disposed pivotal support on the plate, a lever pivoted on the actuating lever, a spring connected at one end to the carrier and at its opposite end to the second lever, said second lever being movable by the actuating lever against a part of the motor as a fulcrum point about which the said second lever is moved by a continuation of the movement of the actuating lever for positioning the spring to impart a snap motion to the carrier, said spring exerting opposing forces on the carrier and actuating lever to hold them in pivotal supporting relation to the plate.

9. In a motor for windshield cleaners, a body plate having a shaft bearing sleeve and a valve seat, said sleeve having on its periphery oppositely facing bearings, a valve engaged on the seat, a carrier for shifting the valve having pivotal support in one of the sleeve bearings, an actuating lever operable from a moving part of the motor and having pivotal support in the oppositely facing sleeve bearing, a spring arranged on one side of the sleeve and having one end connected to the carrier and its opposite end shiftable to oscillate the carrier about its pivot, and a spring-positioning member pivoted on the lever and connected to said opposite spring end for shifting the latter.

10. In a motor for windshield cleaners, a body plate, a valve, a carrier for moving the valve, a spring connected at one end to the carrier for moving the same, a movable spring-positioning member connected to the opposite end of the spring, an actuator for the member pivotally supporting the same and operable from a moving part of the motor, and means arranged in the path of the member for varying its spring-positioning movement.

11. In a motor for windshield cleaners, a movable valve carrier, a spring connected at one end thereto, a spring-positioning member connected at one end to the opposite end of said spring, a movable actuator operable from a moving part of the motor and supporting the member, and means arranged in the path of the member for accelerating the movement of the spring-connected end of said member by and during movement of said actuator.

12. In a motor for windshield cleaners, a valve actuating mechanism comprising a pivoted valve carrier, a spring connected at one end thereto, a movable spring-positioning member connected to the opposite end of the spring for moving the same to opposite sides of a dead center relative to the pivotal mounting of the carrier, an actuator operable from a moving part of the motor and moving the member to initially store up energy in the spring and then to effect a movement of the same over dead center, and means to momentarily accelerate the movement of the member to carry the spring over dead center.

13. In a motor for windshield cleaners, a body plate having upwardly and downwardly facing open bearings, a lever operable from a moving part of the motor and having a return bend, the latter having a depending fulcrum projection alining with a similar projection on the body of the lever, said projections seating in the upwardly facing open bearing for pivotally supporting the lever, a valve carrier pivotally engaged in the downwardly facing open bearing, a spring connected to the valve carrier, and a spring-positioning member pivoted between the lever and its return bend and connected to the spring whereby the latter will act to yieldingly hold both the carrier and the fulcrum projections in their respective bearings against displacement.

14. In a motor for windshield cleaners, a body plate having spaced shoulders, a movable valve carrier, a spring connected to the carrier for shifting the same, a member movable initially for storing up energy in the spring and then to permit expenditure of the stored-up energy to shift the carrier, an actuator connected to the member and

operable from a moving part of the motor for moving the member, and means carried by the member and disposed to alternately engage the shoulders by and during movement of the actuator whereby the change-over from the energy-storing movement to the energy-expending movement of the member will be accelerated.

15. In a motor for windshield cleaners, a body member having upper and lower bearings, a valve carrier freely pivoting in one bearing, an actuating lever operable from a moving part of the motor and freely pivoting in the other bearing, a spring arranged on the carrier side of the bearing and connected to the carrier, and a spring-positioning member supported by the lever outwardly of its pivotal support and connected to the spring under tension whereby the 20 spring will tend to hold the carrier and lever in their bearings.

16. A snap action valve mechanism for fluid motors comprising a valve, a valve carrier, a spring connected at one end to the carrier to operate the same, a lever having its longer arm connected to the opposite end of the spring, spaced stops between which the shorter arm of the lever is movable, and means operable by and during movement of 25 a movable part of the motor for moving said lever to first engage said shorter arm adjacent one or the other of said stops and then continue the lever movement about the engaged stop as a fulcrum to effect a quick 30 shift of said opposite end of the spring for moving the valve.

17. A snap action valve mechanism for fluid motors comprising a valve, a valve carrier, a spring connected at one end to the carrier to operate the same, a lever having its longer arm connected to the opposite end of the spring, and an actuator supporting the lever for bodily movement against a relatively fixed part of the mechanism, said 40 fixed part of the mechanism forming a fulcrum support for said lever whereby on continuation of the movement of the actuator the longer arm thereof will act to shift the spring to a new operative position, said 45 actuator being operable from a moving part of the motor to which the mechanism is attached.

18. A snap action valve mechanism for

fluid motors comprising a valve, a valve carrier, a spring connected at one end to the carrier to operate the same, a lever having its longer arm connected to the opposite end of the spring, an actuator pivotally supporting said lever adjacent the outer end of its shorter arm for bodily movement of said 55 lever, said actuator being operable by and during movement of a movable part of the motor to which the mechanism is attached, and a fulcrum support arranged in the path of bodily movement of said lever for being 60 engaged thereby whereby on continuation of the movement of the actuator on the shorter arm of said lever the longer arm will have its spring shifting movement accelerated.

19. In a motor for windshield cleaners, a casing, a piston therein, a shaft rockable by the piston, a spring snap-action valve mechanism for operatively applying fluid pressure to the piston, said mechanism embodying a spring and a lever, said lever 70 being operable from the piston for moving said spring to opposite sides of the pivot of said lever for actuating the valve of said mechanism, and auxiliary means connecting the shaft to a part of the motor and normally urging said shaft toward its adjacent limit of movement and thereby assisting the lever in shifting said spring.

20. A snap-over valve mechanism for reciprocating fluid motors, comprising a valve 75 and a valve carrier, a spring connected at one end to said valve carrier and adapted to store up energy to effect a movement of the valve at the end of each stroke of the motor, a compound lever having pivotally connected lever parts, one lever part being actuated by a movable part of the motor and having fulcrum support on a part of said motor, and the companion lever part pivoted on said first lever part for bodily movement 80 thereby and having one end connected to the opposite end of said spring to move it to a position for actuating the valve, the opposite end of said companion lever part obtaining fulcrum engagement with a fixed 85 part of the motor.

In testimony whereof, we affix our signatures.
